[57] CLAIM

The ornamental design for an umbrella handle with rotatable-head flashlight, as shown and described.

DESCRIPTION

FIG. 1 is a perspective view of an umbrella handle with a rotatable-head flashlight showing our new design;

FIG. 2 is a side elevational view, the opposite side elevational view being a mirror image thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a perspective view similar to FIG. 1, with the umbrella handle shown rotated 10 degrees from the position shown in FIG. 1 and the rotatable head rotated approximately 180 degrees from the position shown in FIG. 1; and, FIG. 8 is a front elevational view similar to FIG. 5, with the rotatable head rotated 40 degrees from the position shown in FIG. 5.

The broken line showing of an umbrella canopy, a canopy shaft and strap in FIG. 1 are for illustrative purposes only and form no part of the claimed design.
